UNITED STATES PATENT OFFICE.

ARTHUR D. MCPHERSON, OF OAK PARK, ILLINOIS.

BAG-HOLDING DEVICE.

1,118,669.

Specification of Letters Patent. Patented Nov. 24, 1914.

Application filed February 19, 1914. Serial No. 819,638.

To all whom it may concern:

Be it known that I, ARTHUR D. MCPHERSON, a citizen of the United States, residing at Oak Park, in the county of Cook and 5 State of Illinois, have invented certain new and useful Improvements in Bag-Holding Devices, of which the following is a specification.

My invention relates to devices for holding 10 fabric bags open for conveniently filling, and for subsequently releasing the bags.

One of the objects of my invention is to provide a means, for association with a usual filling spout, for firmly and securely holding 15 a bag open, around the mouth of the spout, so that it cannot become unintentionally disengaged, and whereby the bag may be readily released, by the proper manipulation of the device, without the necessity of first lifting 20 the bag and contents off of each supporting spur, or hook, in an effort to remove it, after being filled.

Another object of my invention is to provide a self contained device, of uniform size 25 and best adapted to the standard bag, wherein the parts are properly assembled and relatively disposed and which may, bodily, be attached to filling spouts of varying sizes and dimension and which consequently may 30 be sold as a unitary attachment, ready for convenient and immediate application when received by the purchaser.

Other and further objects of my invention will become readily apparent to persons 35 skilled in the art from a consideration of the following description when taken in conjunction with the drawing wherein—

Figure 1 is an elevation of a usual filling spout, showing my device attached thereto. 40 Fig. 2 is a view of one of the sides, at 90 degrees from the side shown in Fig. 1 and Fig. 3 is a transverse section taken on line 3—3 of Fig. 1.

In all the views the same reference characters are employed to indicate similar parts. 45 5 is the ordinary flour or grain conveying filling spout as used in flour, grain or feed mills, or the like, through which such commodities as grain, bran, flour or meal may

be passed when it is desired to deposit such 50 materials into bags. The superposed hopper 6, may be located at a remote point from the lower end of the spout 5. The spout 5 terminates, at its lower end, as shown in dotted lines, as at 7. Such spouts are usually rectangular in shape and are frequently of size well adapted to fit into the mouth of the standard bag, but sometimes they are made smaller than the bag and for this reason, owing to the irregularity in the varying 60 sizes of the spouts, it will be difficult for a purchaser of one of my bag filling devices to properly dispose the various parts in their co-operative relation upon spouts, of such various dimensions. Therefore I mount the 65 parts of my device on a spout section in the shop in which the device is made, and ship it as a complete entity to be bodily attached to the spout, by blocking in around such spout that may be made of unusually small 70 dimensions.

In carrying my invention into effect I provide a sheet metal spout section, 10 preferably of rectangular form and of size best adapted for the standard bag. It is intended 75 to fit around and to contain the lower end of spout 5 through which the cereals, or other comminuted material is to pass into the bag. When the spout 5 is smaller than the interior of the section 10, its outside dimensions 80 may be increased by nailing on to the spout pieces of wood of suitable thickness to fill in the space between the outside dimensions of the spout and the inside surface of the section 10. After this has been done holding 85 screws may be inserted through the perforations 11 made through the walls of the section 10, and passed into the body portion of the spout 5, to hold the device in proper position thereon.

A disk 12 is provided with a handle 13, secured thereto, as by rivets 14. The handle is provided with a knob 15 by which it may conveniently be rotated. The disk and handle are secured to one wall of the section 10, 95 as by a bolt 16, which passes through the wall of the section and through the wall of the disk, and of the handle, the parts being

secured on the bolt 16 by means of a nut 17 or any other suitable manner that may be adapted for the purpose. The handle 13 is offset, as at 13', to permit the passage of 5 a link 18, between the disk and the handle. The disk 12 may be rotated by the handle upon the axis 16. The link 18 is downturned, as at 19, and is pivoted to the disk, as at 20. The other end is downturned, 10 as at 21, and is pivoted to a crank arm 22 of shaft 24, as at 23. A similar link 18' is upturned, as at 19', and is pivoted to the disk 12, as at 20'. Its other end 21' is also upturned, and is pivoted to a 15 crank arm 22', of the shaft 24' as at 23'.

On opposite sides, of the section 10, and at substantial right angles to the side thereof on which is contained the handle 13, and the mechanism just described, is a rotatable 20 shaft 24. The crank arms 22 and 22' are secured to the shafts 24-24' and by means of which the shafts 24, 24' may be oscillated by movement of the links 18-18' when the handle 13 is rotated substantially one-half 25 of a revolution, as shown in dotted lines in Fig. 1.

Projecting from the sides of the shafts 24-24' are bag engaging spurs 26-26', there being two or more on each of the 30 shafts 24. When the parts are in the position shown in full lines in Fig. 1, the spurs 26 are pointing upwardly, their axes being about 30 degrees from a vertical plane, and in such positions as to firmly retain and 35 hold the bag when it is threaded over the spurs.

When the device is to be used, for holding and supporting a bag in place, the parts are in the positions shown in full lines in 40 Fig. 1 with the handle in a vertical plane and pointing upwardly. It will be noticed that any strain coming on the spurs 26-26', due to the weight of the bag and contents, tending to rotate the shafts 24-24' is impressed upon the crank arms 22-22' that are connected to the links 18-18' and that the pivotal points 23-23' joining the links 18-18' with the crank arms 22-22' of the respective links are located diametrically on 50 opposite sides of the axis of the disk 12 so that any pulling strain on either of the outer ends of the links 18 or 18' will come directly through the axis 16 of the rotating parts and thereby the parts are accurately held and firmly locked in position against 55 accidental or unintentional movement to release the bag.

To release the bag, the handle 13 is rotated upon the axis 16 to the right until it 60 again occupies a vertical plane, with the handle pointing downwardly, at which time the links 18-18' are placed in the positions shown in dotted lines, wherein the crank arms are at substantial right angles to their 65 normal locked positions and the spurs,

26-26', are turned downwardly so that the bag will readily slip therefrom.

To return the parts to the positions shown in full lines, in Fig. 1, it is only necessary to rotate the handle 13 half a revolution, 70 back to the original position, at which time the lower surface of the handle 13, as at 13' will act as a stop to prevent further movement of the handle, by its contact with the link 18' and a similar surface of the handle, 75 on the opposite side of its axis, operates as a stop to the link 18 so that the handle 13 may not be rotated to the left substantially farther than the position shown in Fig. 1.

The general practice of the prior art was 80 to drive sharp pointed nails, or spurs, into the sides of the spout 5 in positions substantially corresponding with those occupied by the rotatable spurs 26-26', of my device, and to thread the bag upon these four 85 or more stationary spurs to hold it in place, and after the bag had been filled it was necessary to lift the entire contents of the bag four or more times before it could be entirely released from the engaging devices. 90 The labor thus entailed upon the operator was very wearying and unnecessary and required the services of a robust, strong attendant to be able to stand the imposed burden. My device may be readily operated by 95 a child as the weight of the filled bag tends to assist in the operation of its release when the handle is intentionally turned for this purpose.

While I have herein shown a single embodiment of my invention for purpose of complete disclosure it is manifest that changes may be made therein within the scope of the claims without departure from the spirit of the invention. 100

Having described my invention, what I 105 claim is:

1. A bag holding device comprising a rectangular spout section, adapted for connection to a material delivery spout; two 110 shafts, one on each side thereof; bearings, for the shafts carried by the walls of the spout section, said bearings having arcuate slots therein; spurs carried by the shafts and extending through the arcuate slots, and means to oscillate said shafts to move the spurs to bag holding and bag releasing position.

2. A device of the character described, comprising a rectangular spout engaging 120 section, having means for connecting to a spout; rotatable shafts, one on each opposite side of the lower end of said section; bag engaging spurs projecting laterally from said shafts; a crank arm on each said 125 shaft projecting in front of an intermediate side of said section; a dished disk pivotally connected at its center to said spout with its convexed side adjacent the wall of the spout, a pair of links connecting said 130

crank arms with said disk at diametrically opposite points near its periphery and a handle projecting laterally from the center of the disk, whereby to oscillate said spurs 5 to bag engaging position and to bag releasing position.

In testimony whereof I hereunto set my

hand in the presence of two subscribing witnesses.

ARTHUR D. McPHERSON.

In the presence of—

FORÉE BAIN,

MARY F. ALLEN.
